UNITED STATES PATENT OFFICE.

BERNHARD M. BESKOW, OF MIAMI, FLORIDA.

GOLF-STROKE REGISTER.

Application filed July 8, 1921. Serial No. 483,228.

To all whom it may concern:

Be it known that I, BERNHARD M. BESKOW, a citizen of the United States, residing at Miami, in the county of Dade and State of Florida, have invented or discovered certain new and useful improvements in Golf-Stroke Registers, of which the following is a specification, reference being had therein to the accompanying drawings.

10 This invention relates to an improvement in golf stroke indicators or registers as set forth in my Patent No. 1,358,698, dated November 16, 1920, and in my pending applications for golf stroke registers, Serial No. 437,198, filed January 14, 1921, and Serial No. 465,872, filed April 30, 1921, the present improvement comprising different means for accomplishing the results stated in said patent and applications.

20 The improved register is preferably adapted to be attached to the wrist of the player, or to the belt, or may, in case of a lady player, be pinned to the shirt waist, and eliminates the necessity of a score card and pencil.

25 In the accompanying drawings Fig. 1 is a plan view of the improved register and showing also a portion of a wrist strap. Fig. 2 is a central cross section on line 2—2, Fig. 3 is a section of the improved register on line 3—3, Fig. 2, showing the series of numerals on the various dials. Fig. 4 is a section on line 4—4, Fig. 2. Fig. 5 is a back view of the register with the casing parts removed, showing the operating levers and tripping devices. Fig. 6 shows some detail parts in perspective.

30 Referring to the drawings, 12 denotes the front or outer casing part and 13 the back or inner part thereof, the said casing parts comprising side walls one of which encircles the other, the outer casing part being provided with lugs 14, which are bent over the inner casing part 13 to hold the two parts together. The inner casing part is preferably provided with struck out bars 15 adapted to receive a wrist strap 11. Centrally located within the casing part 13 is an arbor 16, having its bearings in the casing parts, and fastened to the end of the arbor facing the front part 12 is a disk or dial 17 provided with a series of numerals from 0 to 9 inclusive.

Concentrically grouped around said arbor

and dial are a plurality of rings carrying 55 annular dials 18, 19, 20 and 21. The concentric dial rings are nested or arranged within each other so as to be all in a single plane, for compactness. Dial 18 has a series of numerals 0 to 17, inclusive, and is attached 60 to a ring 22 which is of inverted L-shape in cross section and is concentric with the disk 17 and free to revolve around the latter and within a circular wall 23 which is mounted on a false bottom 24 attached to the 65 casing part 13. The ring 22 is provided with ratchet teeth 25 and the wall 23 is partly cut away as indicated at 27 (Fig. 4) to permit a dog 28 to engage the teeth 25 at the opportune time. The dog 28 is pivoted to 70 the lower or inner side of the dial 19 and revolves with the same. Dial 19 is provided with a series of numerals, 0 to 9 inclusive, and is attached to a ring 29, the two revolving together around dial 18, when actuated upon by a spring pawl 30 (Figs. 2 and 5) secured to an operating lever 31. The spring pawl 30 extends through an opening 32 in the false bottom 24 and engages ratchet 75 teeth 33 on the lower or inner face of the 80 ring 29. The movement of the hand lever 31 is limited by the length of a slot in the side of the casing parts 12 and 13.

The dial 20, having a series of numerals 85 0 to 17 inclusive, is attached to a ring 34, provided with ratchet teeth 35 on the side facing the false bottom 24, and the said ring 34 and the dial 20 are free to revolve together around the dial 19 and the ring 29, and to this end the ratchet teeth 35 are engaged by a spring pawl 36 also fastened to the above-mentioned hand lever 31, said pawl 36 projecting through the opening 32 in the false bottom 24. A circular wall 37 is mounted on said false bottom 24 concentric 90 with a ring 38 of inverted L-shape in cross-section to which ring is attached the dial 21 having a series of numerals 0 to 17 inclusive. The ring 38 is provided with ratchet teeth 39 and said teeth are engaged by a dog 40, 100 when said dog is passing an opening 41 (Fig. 4) cut in the circular wall 37. A torsional spring 42 is attached at one end to the ring 38 and at its other end to the false bottom 24. Similar torsional springs are 105 provided for the other rings and dials. To prevent any backward movement of said rings, when under the influence of the tor-

5 sional springs, each ring is as stated provided with ratchet teeth on its side facing the false bottom 24 and spring pawls 43, 44, 45 and 46 press against these teeth. The 10 pawls are fastened to the lower or inner casting part 13 and project through openings in the false bottom 24 and engage with the ratchet teeth on the respective rings 38, 34, 29 and 22. The repeated movement of the 15 hand lever 31 against the stress of the retracting spring 47, (Fig. 5) turns the various dials a certain distance directly or indirectly, and the numerals on said dials become visible successively through the respective openings 48, 49, 50 and 51 in the front of the casing part 12.

20 The manual resetting of the dials to 0 is effected by the levers 52, 53, 54 and 55, the function of which is to interpose the 25 shields 56, 57, 58 and 59 between the pawls 43, 44, 45, 46, 30 and 36 and the ratchet rings or wheels 38, 34, 29 and 22, thus disengaging said pawls from their respective 30 ratchet wheels. Automatic release for resetting the dial 19 is effected by a pin 60 fastened to the dial 19 and extending downwards through a slot 61 in the false bottom 24, said pin being arranged to strike one of the extension arms 62, carrying the 35 shields 58, at the proper time, thereby forcing said shields between the pawls 30 and 45 and the ratchet teeth 38, thus freeing the arms 62, which are then automatically returned to their original positions, by the 40 stress of the torsional spring 63, the pin 60 throwing the arms 62 back and with them the shields 58, and the pawls are then free to engage with their respective ratchet wheels. The other dials when being reset 45 manually are stopped in their reverse movements by the shoulders 64 and 65 on the pawls 40 and 28 respectively, said shoulders contacting against the sides of the slots 41 and 27.

50 46 The false bottom or diaphragm 24 divides the chamber within the casing afforded by the parts 12 and 13 into two compartments one of which contains the rotary ring dials and returning springs and the other of 55 which contains the pawls and shields co-operating with said rotary ring dials and returning springs.

60 The disk or dial 17 is mounted on the arbor 16 and is not in any way connected 55 with the other dials but is operated separately by the hand lever 66 to which is attached a spring pawl 67 engaging with a ratchet wheel 68 mounted on an arbor 16. A wire 69 extends from said pawl to a lever 60 70 on the hand lever 66, and by lifting up on the lever 70, the pawl 67 is pulled away from its engagement with the ratchet wheel 68 and, thus free, the motion of the arbor 10 is reversed by the stress of the torsional 65 spring 71 and the arbor and the dial 17

returned to their original position. After having been moved forward to partially rotate the dial 17 the lever 66 will be retracted by means of a spring 72.

70 The dial 19, when being reset, is stopped in its reverse movement, under the influence of a torsional returning spring 42, by a pin 73 coming into engagement with a stop lug 74, struck out from the inner casing part 13.

75 At the beginning of each play all the dials are set to 0. After the first stroke the dial 20, representing the score for the hole, is advanced one number by the manual operation of the lever 31 with its spring pawl 36. The dial 19, representing the 80 units of the total score, is actuated by the other spring pawl 30, fastened to the same lever 31 and said dial 19 is also moved forward one number. Dial 21, representing 85 the number of the hole which is being played, is also moved forward one number at the registering of this first stroke, by the action of the dog 40, fastened to dial 20, but after this first stroke the dog is depressed by the inclined plane of the slot 41 90 in the circular wall 37 and from that stroke on until the completion of the strokes for the hole in question the dog slides along inactive within the said wall 37, and the dial 21 remains stationary. Should the 95 score for the hole exceed 9 the dial 19 will be automatically reversed, as hereinbefore explained, and in so doing will allow the dog 28 to engage the ratchet wheel 22 and advance the dial 18, representing tens, one 100 number. When the dial 18 is again advanced to register an additional stroke or to indicate the counting of a penalty, the dog 28 will be depressed and become inoperative, sliding along within the circular 105 wall 23, and the dial 18 will remain stationary until another ten is ready to be registered. The total score for the course is therefore indicated by reading downward 110 the two dials 18 and 19 together.

115 In the playing of a match game the dial 17, representing each hole won by an individual player, is rotated to the extent of one number by means of lever 66 and spring pawl 67, and this number becomes visible in front of opening 67^a in the upper casing part 12.

120 In reading the register as the numerals are shown in Fig. 1, it will be understood that 7 strokes have been registered for the 17th hole of the course, and that the total score so far is 84. The match game dial denotes that 6 holes have been won by the player carrying the register.

125 Having thus described my invention I claim and desire to secure by Letters Patent:

1. A golf stroke register comprising a suitable casing, a concentric series of nested 130 rotary dials for indicating the counts of the

- various phases and plays of the game, manual means, including pawls, for turning said dials, and resetting means, including returning springs, levers and shields, whereby 5 said dials may all be returned to zero.
2. A golf stroke register comprising a suitable casing, concentric and nested dials within said casing for registering the number of strokes for each hole of the course, 10 and the total score of the course, manual means for turning said strokes dial, means, connected with said strokes dial, for operating the total score dials, and resetting means, including returning springs, levers and 15 shields, whereby said dials may all be returned to zero.
3. A golf stroke register comprising a suitable casing, concentric and nested rotary dials within said casing for registering the 20 number of strokes for each hole of the course, the total score of the course, and the number of the hole of the course being played, manual means for turning said strokes dial, means connected with said 25 strokes dial for turning the others of said dials, and resetting means, including returning springs, levers and shields, whereby said dials may all be returned to zero.
4. A golf stroke register comprising a 30 suitable casing, concentric and nested rotary dials within said casing for registering the number of strokes for each hole of the course, the total score of the course, the number of the hole of the course being 35 played, and also for registering the number of holes won by an individual player in a match game, manual means, including pawls, for operating said dials, torsional returning springs connected with said dials, and resetting levers and shields to render said pawls inoperative during the resetting operation.
5. A golf stroke register comprising a 40 suitable casing, a dial for registering the number of strokes for each hole of the course, said dial being provided with a series of numerals, manual means, for rotating said dial to cause the numerals thereon to appear successively through an 45 opening in said casing, and two rotary dials concentric with and operated from said first-named dial and provided with numerals to denote the total score of the course, said concentric dials being nested so as all to be arranged in a single plane, torsional returning springs connected with said dials, and manual means whereby said springs may be rendered operative for resetting said dials.
6. In a golf stroke register, the combination with a suitable casing, of a dial for registering the number of strokes for each hole of the course, said dial being provided with a series of numerals, manual means for rotating said dial to cause the numerals there- 50 on to appear successively through an opening in said casing, two dials, concentric with said first-named dial and provided with numerals to denote the total score of the course, and a dial, also concentric with said 55 first-named dial, for registering the number of the hole of the course which is being played, said concentric dials being nested so as all to be compactly arranged in a single plane. 75
7. In a golf stroke register, the combination with a suitable casing, of a dial for registering the number of strokes for each hole of the course, said dial being provided with a series of numerals, manual means for rotating said dial to cause the numerals thereon to appear successively through an opening in said casing, two dials concentric with said first-named dial and provided with numerals to denote the total score of the course 80 and a dial, also concentric with said first-named dial, for registering the number of the hole of the course which is being played, torsional returning springs for said dials, holding means for normally preventing 85 backward movements of said dials under the influence of said springs, means for releasing said dials from said holding means to permit the returning springs to reset the dials, and stopping means to arrest the 90 backward movements of said dials when returned to their normal positions to indicate 0 on the register, said concentric dials being nested so as all to be compactly arranged 95 in a single plane. 100
8. A golf stroke register comprising a suitable casing, concentric and nested rotary dials within said casing for registering the number of strokes for each hole of the course and the total score of the course, manual means for turning said strokes dial, means, connected with said strokes dial, for operating the total score dials, and automatic resetting means for returning said dials to zero. 105
9. A golf stroke register comprising a suitable casing, a concentric series of nested rotary dials within said casing for indicating the counts of the various phases and plays of the game, manual means, including 110 pawls, for turning said dials, and resetting means, including returning springs, levers and shields, whereby said dials may all be returned to zero, said casing being provided with a false bottom dividing the chamber of 115 said casing into two compartments one of which contains said rotary dials and returning springs and the other of which contains said pawls and shields co-operating with said rotary dials and returning springs. 120
10. A golf stroke register comprising a suitable casing, a concentric series of nested rotary dials within said casing for indicating the counts of the various phases and plays of the game, manual means, including 125

4
pawls, for turning said dials, and manual and automatic resetting means, including returning springs, levers and shields, whereby said dials may all be returned to zero, said casing being provided with a false bottom dividing the chamber of said casing into two compartments one of

which contains said rotary dials and returning springs and the other of which contains said pawls and shields cooperating with said rotary dials and returning springs. ¹⁰

In testimony whereof I affix my signature.

BERNHARD M. BESKOW.
